UNITED STATES PATENT OFFICE.

JOHN KRALUND AND CLARENCE DUCKWORTH, OF BROOKLYN, NEW YORK, AND MARCUS STERN, OF TOLEDO, OHIO, ASSIGNORS TO DOEHLER DIE CASTING COMPANY, OF BROOKLYN, NEW YORK, A CORPORATION OF NEW YORK.

CASTING APPARATUS.

1,300,739.

Specification of Letters Patent. Patented Apr. 15, 1919.

Application filed November 11, 1918. Serial No. 261,972.

To all whom it may concern:

Be it known that we, JOHN KRALUND, CLARENCE DUCKWORTH, and MARCUS STERN, all citizens of the United States, the first 5 two above named residing in the borough of Brooklyn, county of Kings and State of New York, and the third above named residing at Toledo, in the county of Lucas and State of Ohio, have invented certain new 10 and useful Improvements in Casting Apparatus, of which the following is a specification.

Our invention relates to die-casting apparatus and particularly to mechanism 15 whereby the die may be expeditiously and with a minimum of labor opened and closed and locked in closed position during the operation of making die-castings therein. In the preferred form of our device a horizontally movable ram or member to which 20 a portion of the die is secured is reciprocated by power means such as an air cylinder with piston rod and cross head, the movement of the cross head serving to open 25 and close a toggle joint or joints, whereby the member carrying the movable die part is moved forwardly and back and is locked in its forward position in which the die is closed, when the toggle joint is straight- 30ened. With such an arrangement exact adjustments are possible to cause the closing movement of the die to take place at each operation in the same manner and with the same necessary amount of pressure and with 35 a minimum expenditure of time and labor. Such apparatus is adapted to be used in connection with suitable devices for forcing molten metal under pressure into the die, such, for example, as the apparatus de- 40scribed in application of John Kralund, Serial No. 245,263, filed July 17, 1918. The object of our invention is to provide an improved apparatus of the character above briefly described.

45 In order that our invention may be more clearly understood, attention is hereby directed to the accompanying drawings, forming a part of this application and illustrating one embodiment of our invention. In 50 the drawings Figure 1 represents a vertical longitudinal section through an apparatus embodying our invention, certain parts

being shown in side elevation, Fig. 2 is a top plan view of the same, Fig. 3 is a cross section taken on line 3—3 of Fig. 1, and Fig. 4 is a side elevation of the melting pot and molten metal carrier device shown in Fig. 1, certain parts being shown in section.

Referring to the drawings, the mechanism comprising our invention comprises a suitable frame 1 which may be of any suitable form such as that illustrated. This frame or standard 1 is provided on its upper surface with a pair of bearing surfaces, such as the flat surface 2 and 65 the inverted V-shaped surface 3 shown in Fig. 3 on which the frame 4 is mounted for longitudinal adjustment. Frame 4 carries a horizontally disposed power cylinder 5, which is mounted intermediate the side 70 walls of the frame 4 in any suitable manner as on the flanges 6, 6 which are inwardly disposed from the side walls of the frame 4. A top member 7 may be slidably mounted on suitable slideways on frame 4 for a 75 purpose to be explained, and may be provided with a pair of small cover members 8 and 9, adapted to be seated over suitable openings in the top member 7, whereby the mechanism may be inspected. 80

A gate-forming member 10 is shown, and this may be integral with or secured to a suitable melting pot and furnace construction, the melting pot having means for forcing the molten metal into the gate or opening provided in member 10. One portion, 85 11, of a die is secured to the member 10 by suitable means such as the bolts and nuts indicated at 12, 12, this die member having a gate or opening therein registering with 90 the opening in the member 10.

The cylinder 5 is provided with a suitable piston or plunger 13 having a piston rod 14 extending forwardly therefrom through a suitable gland, this piston rod being secured to a block or cross head 15 adapted to reciprocate on a slideway 16, which is carried by the frame 4. The plunger 13 is reciprocated when desired by air or other suitable motive fluid which may be admitted 95 to the cylinder on opposite sides of the plunger by means of pipe connections 17 and 18 provided with suitable valves (not shown). 100

The member 19 of the die, which is adapted to be moved into and out of engagement with the member 11 of the die when the die is to be opened or closed, is suitably secured as by bolts and nuts 20, 20, to the face of a ram or horizontally movable member 21, which is preferably co-axial with piston rod 14 and the cylinder 5, and which is integral with or secured to the slidably mounted top member 7. Operative connection between the cross head 15 and the ram 21 is established by means of a pair of linkages which are adapted to act as toggles to lock the die in its closed position. As illustrated, links 22, 22, are pivoted at their forward ends at 23, 23, to the ram 21 on opposite sides of the latter. Other links 24, 24, are pivoted at their rear ends 25, 25, to horizontal flanges 26, 26, extending inwardly from the sides of frame member 4, the pivots 25 being in longitudinal alignment with the pivots 23. The rear ends of links 22 are pivotally connected to the forward ends of links 24 by means of pins 27, 27, and links 28, 28, have their outer or forward ends pivotally mounted on the same pins 27, 27. The inner ends of links 28 are pivotally secured at 29, 29, to the cross head or block 15. The manner in which the various links referred to are formed is not material, but links 24 may suitably be formed with forked ends through which pins 27 extend, links 22 being pivoted on pins 27 between the forked ends of links 24, and links 28 may be formed with forked ends which are pivotally mounted on pins 27 above and below the top and bottom surfaces of links 24.

With the construction described the forward movement of plunger 13 and cross head 15 into the position shown in the drawings serves to straighten out the toggles formed by links 22 and 24, to press the member 21 forwardly into the position in which the die is closed and is locked in the closed position by the alinement of links 22 and 24. When the die is opened by causing the plunger 13 to move rearwardly in cylinder 5 the inner ends of links 28 are drawn rearwardly, while links 24 swing inwardly about the fixed centers 25, 25, links 22 correspondingly swinging inwardly about their pivots 23 to break the toggles and to open the die by pulling member 21 rearwardly through the link connections 28, 22.

The longitudinal position of frame 4 on standard 1 may be adjusted in accordance with the dimensions of the die members which are to be used for any particular series of casting operations, so that the forward movement of member 21 will be just sufficient to close the die with the proper amount of pressure. This may be accomplished by providing the frame 4 with outwardly extending flanges 30, 30, through

openings in which extend the threaded tie rods 31, 31, the forward ends of which extend through openings in the brackets or flanges 32, 32 integral with or secured to the gate member 10. The frame 4 may be adjusted in correct position on the standard 1 and secured in such position by means of the nuts 33 on rods 31.

Suitable adjustable stops may also be provided to limit the movements of the toggle joints into their straightened positions and to thereby slightly adjust the throw of member 21. These stop members may suitably take the form of a bolt 34 threaded into a suitable opening in the ram 21 and extending rearwardly therefrom, and a bolt or member 35 extending forwardly from the cross head 15, bolt 34 being provided with a head and lock nut, and member 35 with a pair of nuts, for securing the bolts in adjusted position. Member 35 is shown as an extension of piston rod 14, and is provided with a forwardly extending portion 35' adapted to abut against the head of bolt 34 at the end of the forward movement of cross head 15. These stop members may be so adjusted that the forward movement of cross head 15 is stopped when links 22 and 24 are exactly in alinement with each other, in which case links 28 will extend inwardly at right angles to links 22 and 24, as shown. Or the stop members may be so adjusted as to stop the forward movement of cross head 15 when links 22 and 24 have not quite come to exact alinement with each other, in which case the forward movement of member 21 and the die member 19 carried thereby will be slightly lessened.

For purposes of illustration, we have shown a melting pot 36 carried by a frame 37 and containing metal which is kept in molten condition by any suitable heating devices. We have illustrated a mechanism for transferring molten metal under pressure through the gate in member 10 into the die, this being a form of device covered by the said application of John Kralund, Serial No. 245,263, although it is obvious that our present invention is not limited in any way to the use of such a device. In the device illustrated a pivoted carrier or ladle 38 is provided with a nozzle 39 which is adapted to dip under the surface of the molten metal in the melting pot when the ladle device is in one position, so that a charge of the molten metal will flow into the interior of the ladle. When this charge is to be transferred to the die the ladle device 38 is swung into the position shown in Fig. 4 by mechanism which it is not necessary to describe in detail, so that the nozzle 39 will register with the gate opening in member 10, after which the charge is forced into the die by means of air which is caused to flow under pressure through the flexible

connection 40 into the interior of the ladle device 38.

It is obvious that the mechanism we have described results in the effective and rapid opening and closing and locking of the die by the simple operation of the valves admitting air or other motive fluid to the opposite sides of plunger 13 in the cylinder 5. With this device the forward movement 10 of ram 21 and the amount of pressure exerted on the die in closing the same is limited and determined by the position of the links 22 and 24 in their straightened or forward positions. The provision of the 15 stop members on cross head 15 and ram 21 also results in taking to a considerable extent the stresses which otherwise would be carried by the pivot pins 25 and 23. While the form of device illustrated and described 20 is thought to be most effective, it should be understood, however, that our invention is not strictly limited to the exact details of construction described and that our invention is not necessarily limited to the use of 25 a power cylinder such as that illustrated since other forms of mechanism may be used for causing the reciprocation of a member such as the cross head 15 or for otherwise operating the toggle construction.

30 What we claim is:—

1. In a casting machine, the combination of a reciprocable actuating member, a member to which a portion of a die may be secured, movable into positions to close and 35 open the die, a frame, and toggle connections between said frame and members adapted to move said second member and to straighten the toggle, to form a lock, when said member has been moved to close 40 the die.

2. In a casting machine, the combination of a power cylinder, a piston, piston rod and cross head therefor, a member to which a portion of a die may be secured, movable into positions to close and open the die, a frame, and toggle connections between said frame, cross head, and member, adapted to move said member and to straighten the toggle, to form a lock, when 50 said member has been moved to close the die.

3. In a casting machine, the combination of a fixed frame, having a slideway, a block mounted to reciprocate thereon, a member to which a portion of a die may be secured, movable in the same directions as said block, to close and open the die, a link pivoted to said member, a link pivoted to said frame at one end and pivoted at its opposite end 60 to the free end of said first link, said links being adapted to extend in an approximately straight line when the die is closed, and a link pivotally connecting the pivotal connection between said first two links and said block, and adapted to close or open the 65

toggle formed by said first two links, as said block moves in one direction or the other.

4. In a casting machine, the combination of a fixed frame, a power cylinder carried thereby, a piston, piston rod and cross head for said cylinder, a member to which a portion of a die may be secured, movable in the axial direction of said cylinder into positions to close and open the die, and connections for moving said member and locking the same in the forward position in which the die is closed, comprising links pivoted to said member and extending rearwardly therefrom, links pivoted to said frame and extending forwardly therefrom, pins pivotally connecting the adjacent ends of said rearwardly and forwardly extending links, said links being adapted to extend in straight lines when said member is in its forward position, and links pivotally connected to said pins and extending inwardly therefrom to pivotal connections with said cross head.

5. In a casting machine, the combination of a fixed frame, a member mounted to reciprocate, a member to which a portion of a die may be secured, movable in the same directions as said first member, to close and open the die, a link pivoted at one end to 90 said second member, a link pivoted at one end to said frame and at its opposite end to the free end of said first link, said links being adapted to extend in an approximately straight line when the die is 100 closed, parallel to the direction of movement of said first member, and a link pivotally connecting the pivotal connection between said first two links and said first member, and adapted to close or open the toggle 105 formed by said first two links, and to move said second member forward or back, as said first member moves forward or back.

6. In a casting machine, the combination of a frame, a member mounted to reciprocate 110 thereover, a member to which a portion of a die may be secured, links pivotally secured to said second member and frame, and to each other, to form a toggle, adapted to straighten when said second member is in 115 forward position, a link pivotally connected to said first member and to the pivotal connection between said first two links, to operate the toggle formed by said first two links, and adjustable stop means for limiting the forward movement of said first member and thereby adjusting the forward position of the toggle.

7. In a casting machine, the combination of a frame, a member mounted to reciprocate 125 thereover, a member in advance of said first member, to which a portion of a die may be secured, links pivoted to said frame, second member and first member, and to each other, to form a toggle, operable from said 130

first member and adapted to straighten when said members are in forward position, and adjustable stop means carried by said first and second members, adapted to engage at 5 the end of the forward movements of said members to adjust the forward position of the toggle.

8. In a casting machine, the combination of a frame, a member mounted to reciprocate 10 thereover, a member in advance of said first member, to which a portion of a die may be secured, toggle connections between said frame and members adapted to move said second member back and forth and to 15 straighten the toggle when said second member moves into forward position, a member adapted to carry another portion of the die, against which the first portion of the die is to be closed, and adjustable 20 connections between said last member and

said frame, for adjusting the position of said frame with respect to said last member.
